UNITED STATES PATENT OFFICE

HERBERT F. OBERGHELL, OF RIVER FOREST, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

ELECTROMAGNETIC DEVICE

Application filed December 14, 1931. Serial No. 580,895.

This invention relates to electromagnetic devices in general, but more particularly to electromagnetic devices such as induction coils and the principal object of the invention resides in the provision of a new and improved type of induction coil in which the spool heads of the coil are formed of moulded material which serves to support the coil as a unit and at the same time constitute terminal blocks for extending connections to the windings of the coil or for connections to other apparatus.

A further object of the invention resides in means in the combined spool heads and terminal blocks for protecting and segregating the various conducting wires extending from the windings of the coil to the terminal connections on the spool head.

Further objects of the invention are concerned with the design of a new and improved induction coil which is economical to manufacture, is compact and sturdy in structure and presents a number of desirable advantages over previous types of induction coils.

It has been the practice, in the past, to construct induction coils or electromagnetic devices with the windings of the coils wound directly around a laminated core and with a circular or disc shaped insulated spool head forced over each end of the core to hold the windings in place. With this type of structure it will be easily seen that with rough handling, temperature changes or other causes, the structure of the coil is easily damaged, the windings broken and the spool heads broken off; resulting in an inoperative or defective coil which must be replaced or repaired. Similarly no provisions were made for protecting or supporting the short connecting leads extending to the windings. It was common practice to connect these directly to a separate terminal block mounted adjacent the induction coil and this structure therefore necessitated the utilization of considerable valuable space when the device is

incorporated, for example, in a telephone substation apparatus. By providing a device according to the invention the above difficulties and objectionable features are obviated.

The invention is disclosed in the accompanying drawing in which Fig. 1 shows a top view of the preferred embodiment of the invention. Fig. 2 is a side elevation partly in section; while Fig. 3 shows a perspective view of the device with the windings removed.

The induction coil, according to the invention, comprises primarily a laminated core 4, the opposite ends 5 and 8 of which are bent downward at right angles to the main portion of the core 4. These ends 5 and 8 are moulded directly into the combination spool heads and terminal blocks 6 and 7. These blocks 6 and 7 may be formed of insulation material such as a phenolic condensation product known to the trade as "bakelite". By being poured into a mould in which the laminated core 4 is placed a rigid, sturdy and compact structure results which can be of any desired shape and configuration, and due to the extension pieces 5 and 8 the blocks 6 and 7 will be prevented from being twisted and turned and separated from the core. The various coil windings 9 are wound directly upon and suitably insulated from the core 4 between the blocks 6 and 7, and as is well known, these induction coils may have several separate and distinct windings so that a plurality of terminals must be provided for the connecting leads. By providing a structure in which the spool heads 6 and 7 are moulded directly upon the core 4 a structure is provided which will not be affected by moisture or other climatic conditions. Furthermore, the need for providing separate fastening means for holding together the plurality of separate laminations of the core 4 is obviated.

In order to provide a means for mounting and supporting the coil as a unit the screw

holes 10 in block 6 and 11 in block 7 are provided.

The terminal portion of the blocks 6 and 7 provides a means for accommodating the terminal screws, such as 12, 13, 14 and 15 for example in block 6; similar screws being provided in the block 7. The terminals 12, 13 and 15 are provided with soldering tags 17 to which the various connecting leads 10 extending from the windings of the induction coil are connected. The soldering tags 17, as clearly shown in Fig. 2, are riveted to brass studs 18 which are moulded directly into the insulated block. These brass studs 18 are tapped to receive the terminal screws. Any number of soldering lugs and associated terminal screws may be provided. If it is desired however not to provide a soldering tag 17 the stud 16 is only provided and the screw such as 14 in block 6 is threaded into stud 16 and serves as a distributing point for apparatus other than the windings of the coil.

Projecting upwardly from the block 6, for example, and extending in close proximity to the terminal posts 12 and 13 are a series of protuberances or extensions 20 which are moulded integral with the block. Similar projections 21 surround the screw terminals 14 and 15 as is clearly shown in Fig. 3. The purpose of these projections around each terminal is to provide a means for securely holding and locking the spade terminal clips to which the connecting wires are attached, to the block. In placing the spade clips in position, the screw terminal 12 for example is loosened a sufficient distance out of the stud 18, so that the spade clip can be slipped under the head after which the screw can be turned down on top of the clip. In case it should occur that the screws become slightly loosened up while the device is in use, it will be clearly seen that the projections 20 and 21 will prevent the spade clips from completely pulling away from their associated terminal posts, thereby lessening the chances of causing any disconnection of the circuits to which the induction coil is connected.

In case it is desired, any number of additional spade clips and their associated connecting leads may be attached to the same terminal posts. By placing suitable extension studs on the mounting bolts provided in the holes 10 and 11, additional terminal posts may be provided so that other spade clips may be attached thereto and locked in position on the projections 26 and 27 formed in the blocks 6 and 7 respectively. The terminal posts 12, 13, 14 and 15 may likewise serve as supporting or holding means for additional apparatus such as, for example, condensers, buzzers, etc. in addition to serving as terminal posts for the connecting leads.

65 The connecting leads 30 from the windings

of the coil 9 which are soldered to the soldering tags 17 are arranged to lie in the slots 25 separated by projections 24 so there will be no danger of causing a short circuit or crossover between them. The slots 25, 70 as is clearly seen in the block 7 of Fig. 3, are situated so that the connecting leads 30 are enabled to extend directly outwards from the winding of their respective coils. The reason for this is that as additional layers 75 of windings are placed on top of one another there will be no danger of shearing, crushing or breaking the connecting leads and no special provisions for protecting these connecting leads are necessary as was in the 80 prior types of induction coils. The slots 25 are cut into the spool head slightly and extend upward to a point on about the level of the ends of the soldering tags 17. Furthermore, due to the fact that the blocks 6 and 7 are inherently constructed of insulating 85 material no special provisions are required for insulating the connecting leads and bare wire conductors may be used, in which case 90 it may be desirable to fill up the hollow space 95 in which the conductors lie in each block with some suitable insulating compound.

What is claimed is:

1. In an electromagnetic device, a laminated core, a combination spool head and terminal block moulded on each end of said core, each end of the core having a portion extending at an angle therefrom in the block for securely holding said blocks in spaced 100 relationship on said core.

2. In an electromagnetic device, a laminated core having a downwardly projecting portion extending from each end thereof, a spool head moulded on each end of said core around said projections and held in position 105 thereby, terminal means moulded in the top of said spool head for attachment of connecting wires, and means in the spool heads for supporting said device as a unit.

3. In an electromagnetic device, a laminated core having a projection formed on each end thereof, a combination spool head and terminal block formed around each of said projections, said blocks securely binding together the laminations of said core, and a plurality of terminal studs moulded directly 115 into the top of said blocks.

4. An electromagnet comprising a core made up of a plurality of laminations, the ends of the core being bent at an angle, spool 120 heads supported on each end of the core, said spool heads binding together said laminations, the angular ends of the core preventing displacement and turning movement of the spool heads, and a plurality of terminals mounted directly on top of said spool heads on the opposite side from the angular end of the core.

5. An electromagnet comprising a core and windings, each end of the core being bent 125

downward at an angle, spool heads moulded on each end of the bent portion of the core, said bent portions preventing displacement of the spool heads, terminal posts mounted on the top of said spool heads on the opposite end from the downward portions of the core, and a plurality of slots formed in the side of each spool head to protect and insulate the conducting wires extending from the windings of the coil to the terminal posts.

In witness whereof, I hereunto subscribe my name this 11th day of December, A. D. 1931.

HERBERT F. OBERGFELL.
